UNITED STATES PATENT OFFICE

91,449

DESIGN FOR A HOOD AND COWL ASSEMBLY

Fred M. Zeder, Detroit, Mich., assignor to
Chrysler Corporation, Detroit, Mich., a corpora-
tion of Delaware

Application October 28, 1931. Serial No. 41,553

Term of patent 3½ years

To whom it may concern:

Be it known that I, FRED M. ZEDER, a citizen of the United States, residing at 1651 Wellesley Drive, Detroit, in the county of Wayne and State of Michigan, have invented a new, original, and ornamental Design for a Hood and Cowl Assembly, of which the following is a specification, reference being had to the accompanying drawing, forming part thereof, in which:

Fig. 1 is a side elevation of my new hood and cowl assembly.

Fig. 2 is a front perspective view of the new hood and cowl assembly.

I claim:

The ornamental design for a hood and cowl assembly substantially as shown.

FRED M. ZEDER.
